ALTERNATING CURRENT-DIRECT CURRENT
FLATIRONMaurice H. Graham, Minneapolis, Minn., assignor
to General Mills, Inc., a corporation of Delaware

Application November 24, 1948, Serial No. 61,845

12 Claims. (Cl. 219—25)

1

The present invention relates to flatirons and more particularly to a flatiron which may be used selectively with both alternating current and direct current supplies.

The great majority of household appliances such as flatirons are designed for use with alternating current supplies because alternating current predominates in household electrical systems. There are, however, a number of installations in which direct current is utilized. One such use of direct current is in hotels in major cities of the country. It is therefore desirable to provide a flatiron and particularly a flatiron of the small or traveling type which may be utilized selectively on either alternating current or direct current as the case may be.

In alternating current flatirons of known construction, it is customary to provide a thermostatic switch which automatically cuts the heating element on and off to maintain the desired temperature at the soleplate of the iron. It is not practical to use such a thermostatic switch with a direct current supply because the making and breaking of the electrical circuit would involve considerable arcing at the contacts of the switch and would soon destroy these contacts and make the iron inoperative. While irons have been made in the past for use with direct current, it is necessary in such case that the wattage of the heating element be kept low enough so that the element may be energized continuously without unnecessary or dangerous heating of the iron.

With the foregoing problems in mind, it is one object of the present invention to provide a flatiron construction suitable for selective use with alternating current and direct current.

It is a further object to provide a flatiron construction in which a thermostatic switch is incorporated in the circuit for alternating current operation.

It is a further object to provide means for cutting such a thermostatic switch out of the circuit when the flatiron is to be used for direct current operation.

Still another object of the invention is the provision of an auxiliary resistance which may be included in the heating element circuit for direct current operation in order to cut down the effective heating of the element during such use.

2

A still further object is the provision of suitable switch or control means for selective connection of the parts in the desired relation for A. C. and D. C. operation.

Other objects and advantages of the invention will be apparent from the following specification in which a preferred embodiment of the invention is described.

In the drawings which form a part of this application, Figures 1, 2, and 3 constitute an exploded view of a flatiron construction according to the present invention.

Figure 1 shows the handle and shell assembly together with details of the control switch.

Fig. 2 is a perspective view of the thermostatic switch mechanism, and

Fig. 3 is a perspective view of the soleplate and heating element of the iron.

The parts in the three figures are connected by wiring to show their operative relationship to each other.

Fig. 4 is an exploded view of a modified circuit arrangement.

The flatiron involves the usual soleplate 10. This soleplate is provided with a recessed or channeled area 11 for accommodation of a suitable heating element 12. A pressure plate 13 is positioned above the heating element 12 and forces the latter firmly against the bottom of the channels 11 in the soleplate in order that these parts may be held in good heat conductive relation. Clamping screws 14 hold the pressure plate against the heating element and soleplate.

The heating element 12 includes two resistance ribbons 15 and 16 which are wound in parallel spirals on the respective insulating sheets of the heating element. Resistance 15 is provided with terminals 17 and 18 at its respective ends, while heating element 16 has corresponding terminals 19 and 21 respectively. A bridging contact 22 connects the terminals 18 and 21 of resistances 15 and 16 at one end. Thus terminals 17 and 19 constitute first and second leads at the extreme ends of the combined heating element consisting of individual resistance elements 15 and 16, while terminal 18 constitutes a third lead at the intermediate point between portions 15 and 16.

Along the central longitudinal line of soleplate 10 a recess or channel 23 is provided. Holes 24 in the bottom of channel 23 at the forward

end thereof are designed to accommodate retaining pins 26 for a thermostatic control element or bar 25. Pins 26 hold the forward end of thermostatic bar 25 firmly against the bottom of channel 23 so that the thermostatic bar 25 is in good heat conductive relationship with the lower portions of soleplate 10. Thus the thermostatic bar reflects accurately the heat conditions at the bottom of the soleplate in known manner.

One end of thermostatic bar 25 is provided with an insulating button 27 which engages the downwardly extending arm 28 of switch contact arm 29. The other end 31 of contact arm 29 is adapted to be mounted at 32 on an insulating block 33 fastened to a supporting bracket 34. Bracket 34 is fastened to soleplate 10 by a screw 35.

Since the major portion of thermostatic bar 25 is mounted within channel 23 at a level below the pressure plate 13, and since the contact arm 29 is mounted on insulating block 33 above pressure plate 13, the pressure plate will necessarily be provided with suitable openings (not shown) through which the end 27 of thermostatic bar 25 may engage the downward projection 28 of the switch arm 29.

One end 36 of a second switch arm 37 is similarly mounted at 38 on insulating block 33. Switch arms 29 and 37 are provided with cooperating contacts 39 and 41 respectively. The resilience of the switch arms is such that they are normally urged toward each other so that the contacts 39 and 41 will be engaged. However, when the iron reaches a temperature in the range desired for operation, the thermostatic bar 25 will flex upwardly and will lift the switch arm 29 so that contact 39 is separated from contact 41 and the circuit through the thermostatic switch is broken.

The temperature at which this opening of the contacts takes place may be adjusted in known manner by suitable adjustment of the position of switch arm 37. This adjustment is obtained by means of an insulating projection 42 mounted at the lower end of an adjusting rod 43. Rod or shaft 43 is threaded at 44 for engagement with a suitable supporting block (not shown) fastened to the underside of the shell or other structure of the flatiron. A control knob 45 is fastened to the upper end of shaft 43 and is located above the shell 46 of the iron where it is readily accessible to the user. A pointer 47 on control knob 45 cooperates with suitable indicia 48 on the shell 46 or on a suitable index plate fastened to said shell in order to indicate to the user the temperature at which the thermostatic switch is set to operate.

The threads 44 are so arranged that as the knob 45 is rotated in a counterclockwise direction in the figure to the off position, the contact arm 37 will be forced downwardly so that contact 41 is finally separated from contact 39 even when thermostatic bar 25 is in its cold or lower position.

Since the operation of a thermostatic switch of this type and its adjustment are well known to those skilled in the art, no further description thereof will be given. It should be noted that any equivalent form of temperature control switch which is customarily used in the flatiron field may be utilized successfully in the present invention.

Above the shell 46 of the flatiron, a suitable handle 49 is provided. At the rear of this handle an electric supply cord 51 is mounted. This

supply cord is adapted for connection to the usual outlet in the wall of the building in which the flatiron is to be used. The individual conductors 52 and 53 of the supply cord are led downwardly through the handle 49 to the interior of the iron where these wires are connected to suitable terminals 54 and 55, shown only schematically in the drawing.

In order to adapt the iron for selective use with alternating and direct current supplies, a control switch arm 56 is mounted at the end of a rotatable shaft 57 journaled in the handle 49. Switch arm 56 is insulated from the control shaft 57 in known manner.

A manually operable control knob 58 is fastened to the upper end of shaft 57 where it is readily accessible to the user. An index mark 59 on handle 49 cooperates with suitable indicia 61 and 62 on knob 58 to indicate to the user the A. C. and D. C. positions of switch arm 56.

Arm 56 carries a contact 63. In the A. C. position of the switch arm 56 as shown in Fig. 1, this contact 63 engages a cooperating fixed contact 64 carried on an insulating block 65 inside the flatiron. Block 65 also supports an additional contact 66 which is engaged by contact 63 when switch arm 56 and knob 58 are rotated to the D. C. position.

To connect the various parts in electrically operative relationship, the following circuit is provided.

A wire 67 connects terminal 55 of supply conductor 53 to the control switch arm 56. A further wire or conductor 68 connects the fixed contact 64 of the control switch to the end 31 of thermostatic switch arm 29. Conductor 69 connects the end 36 of the other thermostatic switch arm 37 to the terminal 18 of heating element ribbon 15. The other terminal 17 of heating element ribbon 15 is connected by wire 71 to the terminal 54 of supply conductor 52.

The wiring just described completes the circuit for alternating current operation of the iron. In this circuit the current from the supply terminals 54 and 55 passes through the control switch arm 56 through the thermostatic switch contacts 39 and 41 and through the heating element resistance ribbon 15. Since switch contacts 39 and 41 are in series with the element 15, the operation of the thermostatic switch by thermostatic bar 25 will make and break the circuit through the heating element 15 to control the operating temperature of the flatiron in known manner.

When the control knob 58 is rotated to the D. C. position so that switch arm 56 engages the contact 66, the circuit from the switch arm will be completed by a wire 72 to terminal 19 of the secondary heating element resistance ribbon 16. In this D. C. position of the control switch, the thermostatic switch contacts 39 and 41 will no longer be in the circuit, since the circuit is broken at contact 64. Thus, in this case, the circuit from the supply cord 51 will be completed in the following manner. From supply conductor 53 the current will pass to terminal 55 through wire 67, switch arm 56, contacts 63 and 66, wire 72, terminal 19, resistance element 16, terminal 21, cross contact 22, terminal 18, main resistance ribbon 15, terminal 17, wire 71, and terminal 54 back to the other supply conductor 52. With the thermostatic switch contacts 39 and 41 out of the circuit, there is no possibility of arcing at these contact points. The thermostatic bar 25 will, of course, bend under the heat conditions of the

soleplate 10 and will open and close the switch contacts 39 and 41, but this operation will have no effect on the electrical circuit itself.

The value of the resistance of the main heating element 15 is so chosen that when the iron is operating in the A. C. circuit, the element 15 will operate at a high wattage. In other words, element 15, when in circuit alone, is capable of producing much more heat than is normally withdrawn from the soleplate 10 in normal operation of the iron.

For example, a resistance of substantially 12 ohms for element 15 will give an iron with a rating of 1100 watts, when used with 115 volt alternating current of the usual household type. The use of this high wattage for A. C. operation is well known and understood and provides an iron which responds quickly to actual ironing conditions and which tends to maintain even soleplate temperatures under the control of the thermostat 25 and thermostatic switch elements 39 and 41.

However, if resistance element 15 were used alone when the iron is operated with a direct current supply, there would be a dangerous tendency for the soleplate 10 to overheat. It is possible that the resistance 15 might burn out due to the extremely high temperatures which it could reach if the current were not interrupted. Since the thermostatic switch 39, 41 is not in circuit and cannot interrupt the current to the heating elements, it is accordingly desirable to throw the auxiliary resistance 16 into the circuit for D. C. operation in the manner described.

The value of resistance element 16 is such that when elements 15 and 16 are combined in series as in the direct current circuit, the wattage of the combined resistances will be much reduced. In a preferred form of the invention the value of this resistance is substantially equal to that of the main heating element. Thus in the specific case above, where element 15 has a resistance of 12 ohms, the use of a similar value for resistance 16 will yield an iron with only half the rating, i. e., 550 watts.

While this means that the heating of the soleplate 10 will be much slower during direct current operation, this same thing is true in connection with all direct current irons at the present time. Therefore the direct current operation of the present iron is at least as good as that of the direct current travel irons or similar constructions which are now available. At the same time the present construction offers the very great advantages of use with alternating current supplies at higher wattage for improved flatiron operation whenever such alternating current supplies are available. Thus it is unnecessary for the user to own two irons, one for household use with alternating current and a separate iron for traveling and for direct current use. The advantages of the two types of irons are combined in a single construction in which it is only necessary to adjust the position of the control knob 58 to utilize the iron selectively with both direct and alternating current.

In the modified circuit arrangement shown in Fig. 4, the circuit connections are such that the thermal switch designed to control operation of the flatiron on A. C. current is effectively bypassed during D. C. operation. In this figure the parts which are similar to corresponding parts in Figs. 1 to 3 are given numbers corresponding to those of the previous figures, but with 100 added. The parts are shown in Fig. 4 75

in the A. C. position of operation in which the main heating resistance 115 for flatiron soleplate 110 is connected in series with the thermal switch directly across the current supply terminals on supply lines 52 and 53. This circuit may be traced from supply line 52 through terminal 154, lead 171 to terminal 117 at one end of main heating element 115, thence to terminal 118 at the other end of the main heating element and through lead 169 to terminal 136 at one contact arm 137 of the thermal switch. When contacts 139 and 141 of this switch are closed, the circuit is completed through the other switch arm 129, its terminal 131, lead 168, terminal 177, and lead 167 back to the other supply line 53. Movement of thermostat 125 in response to predetermined soleplate temperatures causes engagement of insulating portion 127 with the down-turned end 128 of contact arm 129 to open and close the switch contacts. Adjusting shaft 143, threaded at 144 and provided with an insulating button 142, controls the position of the other contact arm 137 in the same manner previously described for the first embodiment.

25 In this modification, the auxiliary resistance 116, which is preferably associated with the soleplate as in the previous case, is connected at one end to terminal 118 and has its other terminal 119 connected by lead 174 to one contact 173 of the selective A. C.-D. C. control switch 156. Arm 172 of this switch is connected at one end 170 by lead 171 to terminal 177. The position of switch arm 172 is controlled by shaft 157 and knob 158 having A. C. and D. C. indicia co-operating with the index mark 159 as in the previous cases.

25 In the A. C. position of Fig. 4, the switch 156 is open and resistance 116 is out of circuit. When the control knob 158 is moved to the D. C. 40 position, the switch 156 will be closed, so that the switch, together with leads 171, 174, and auxiliary resistance 116 will effectively bypass the thermal switch contacts 139 and 141. In this D. C. position, the auxiliary resistance 116 45 will also be placed in series with resistance 115 across the supply lines 52 and 53. Passage of current through auxiliary resistance 116 will depend on the position of the thermal switch contacts 139 and 141. In any event, the bypass 50 circuit with its included resistance will substantially prevent arcing at these contact points and will provide a means for continuously energizing the main heating element 115 to a greater or lesser degree. Thus the bypass circuit of Fig. 55 4 provides a modified arrangement for achieving certain of the objects of the present invention.

Various changes in the specific construction shown in the drawings will be readily apparent to those persons skilled in this art now that applicant has taught the essential features of the present invention. Applicant intends to include in his invention all such modifications, changes, and variations as fall within the spirit and scope of the attached claims.

65 Now, therefore, I claim:

1. A flatiron for selective automatic and non-automatic operation comprising a soleplate, a pair of electric heating elements operatively associated with the soleplate for heating it, an automatic switch responsive to temperature of the flatiron, a pair of terminals for connection to a current supply, and a control switch having a switch arm movable between two positions; means connecting only one of the elements and the automatic switch in series with each other

directly across the terminals when the control switch arm is in one position, and means connecting both of the elements in series with each other directly across the terminals when the control switch arm is in another position.

2. A flatiron for selective automatic and non-automatic operation comprising a soleplate, a pair of electric heating elements operatively associated with the soleplate for heating it, an automatic switch responsive to temperature of the flatiron, a pair of terminals for connection to a current supply, and a control switch having a switch contact arm movable between two positions; means connecting one of the elements and the automatic switch in series with each other across the terminals when the control switch contact arm is in one position, and means cutting the automatic switch out of circuit and connecting both of the elements in series with each other across the terminals when the control switch contact arm is in another position.

3. A flatiron for selective operation with alternating and direct current comprising a soleplate, an electric heating element operatively associated with the soleplate for heating it and having a first lead at one end, a second lead at the other end, and a third lead connected at an intermediate point on the element, an automatic switch opening and closing in response to temperature changes in the flatiron, a pair of current supply terminals, a control switch having first and second switch contacts and a main switch arm movable between an A. C. position in which it engages the first contact and a D. C. position in which it engages the second contact, and an external control knob operatively connected to the switch arm for movement of the latter between said positions, one of said supply terminals being connected directly to the first heating element lead, the other of said supply terminals being connected directly to said switch arm, said automatic switch being connected between said first switch contact and the third heating element lead, and said second switch contact being connected directly to the second heating element lead.

4. A flatiron for selective automatic and non-automatic operation on alternating and direct current respectively comprising a soleplate, a main electric heating resistance operatively associated with the soleplate for heating it, a thermal switch automatically opening and closing in response to increase and decrease of the temperature of the flatiron above and below a predetermined range, an auxiliary resistance, a pair of terminals for connection to a current supply, a selective manual control switch having a switch contact arm movable between A. C. and D. C. positions, circuit means connecting only the main resistance and thermal switch in series with each other and directly across the terminals when the control switch contact arm is in its A. C. position, and additional circuit means connecting said main and auxiliary resistances in series with each other and directly across the terminals when the control switch contact arm is in its D. C. position.

5. A flatiron according to claim 4 in which the circuit means also cuts the thermal switch out of circuit when the control switch contact arm is in its D. C. position.

6. A flatiron according to claim 4 in which the auxiliary resistance bypasses the thermal switch when the control switch contact arm is in its D. C. position.

7. A flatiron for selective automatic and non-automatic operation on alternating and direct current respectively, comprising a soleplate, a main electric resistance element operatively associated with the soleplate for heating it, a thermal switch automatically opening and closing in response to temperature deviations above and below a predetermined flatiron temperature range to be maintained, a pair of terminals for connection to a current supply, a selective manual control switch having a contact arm movable between A. C. and D. C. positions, circuit means connecting only the main electric resistance element and thermal switch in series with each other directly across the terminals when the control switch contact arm is in its A. C. position, and additional circuit means effectively bypassing the thermal switch and substantially decreasing the heating effect of said main resistance element when the control switch contact arm is in its D. C. position.

8. A flatiron according to claim 4 in which the auxiliary resistance is substantially equal to the main heating resistance.

9. A flatiron according to claim 4 in which the auxiliary resistance is substantially equal to the main heating resistance, and the auxiliary resistance is operatively associated with the soleplate for transmission of heat to the latter.

10. A flatiron according to claim 4 in which the main heating resistance is substantially 12 ohms.

11. A flatiron for selective automatic and non-automatic operation, on alternating and direct current respectively, comprising a soleplate, at least two electric resistance elements operatively associated with the soleplate for heating it, a thermal switch automatically opening and closing in response to temperature deviations above and below a predetermined flatiron temperature range to be maintained, a pair of terminals for connection to a current supply, a selective manual control switch having a contact arm movable between A. C. and D. C. positions, circuit means connecting at least one resistance element comprising a predetermined total resistance in series with the thermal switch directly across the terminals when the control switch contact arm is in its A. C. position, and circuit means cutting the thermal switch out of circuit with the terminals and connecting at least one resistance element comprising a greater predetermined total resistance in circuit across the terminals when the control switch contact arm is in its D. C. position.

12. A flatiron for selective automatic and non-automatic operation on alternating and direct current respectively, comprising a soleplate, a main electric resistance element operatively associated with the soleplate for heating it, a thermal switch automatically opening and closing in response to temperature deviations above and below a predetermined flatiron temperature range to be maintained, a pair of terminals for connection to a current supply, a selective manual control switch having a contact arm movable between A. C. and D. C. positions, circuit means connecting only the main electric resistance element and thermal switch in series with each other directly across the terminals when the control switch contact arm is in its A. C. position, and circuit means cutting the thermal switch out of circuit with the terminals and continuously connecting at least said main resistance element in circuit across the terminals when the

control switch contact arm is in its D. C. position.
